UNITED STATES PATENT OFFICE

2,560,639

CONTINUOUS CASTING OF METAL

Jean V. Giesler and Hugh E. Kaserman, Knoxville, Tenn., assignors to Robertshaw-Fulton Controls Company, Knoxville, Tenn., a corporation of Delaware

Original application July 7, 1947, Serial No. 759,360. Divided and this application December 13, 1948, Serial No. 64,966

4 Claims. (Cl. 22—57.2)

1

This invention relates to the continuous casting of metal and more particularly to an apparatus for such continuous casting, this application being a division of our application Serial No. 759,360, filed July 7, 1947, for Continuous Casting of Metal.

Heretofore various processes and apparatus have been proposed for the continuous casting of metals. In some of these molten metal has been introduced into a stationary cooled mold and continuously withdrawn from the mold by mechanical means. In others molten metal has been introduced between moving molds and the resulting ingot discharged through an opening between the moving molds. Various means have also been employed to adjust the speed of the ingot with respect to the rate of pouring of the molten metal so that the ingot is cooled and hardened before being withdrawn from the mold. Some of these controls employ photoelectric eyes influenced by the light emanating from the congealing metal in the hardening zone to regulate the speed of withdrawal of the ingot. Others employ for this purpose electrical contacts actuated by the level of the molten metal in the mold, and still others utilize the torque required to drive the moving molds to regulate the speed of emission of the ingot. All of these prior processes and apparatus are subject to disadvantages and uncertainty of operation with consequent undesirable structural defects in the ingot.

It is accordingly an object of this invention to provide a novel apparatus for the continuous casting of metal which is not subject to the uncertainties and disadvantages of operation of prior proposed devices and which will produce ingots of uniform structural characteristics.

Another object of this invention is to provide a novel apparatus for the continuous casting of metal in which the metal is cast between vertically disposed continuously moving molds and withdrawn as an elongated ingot of relatively small cross sectional dimension in at least one direction.

Another object of this invention is to provide such a novel apparatus in which novel means are employed to regulate the speed of the molds with respect to the rate of pour of the molten metal.

Other and further objects will become apparent as the description of the invention proceeds.

One embodiment of the present invention is shown in the accompanying drawings and de-

2

scribed hereinafter to illustrate apparatus coming within its scope, but it should not be construed as defining the scope of this invention, as reference should be had to the appended claims for this purpose.

In these drawings,

Fig. 1 is a front view of one embodiment of our novel casting machine;

Fig. 2 is a side view of the embodiment of Fig. 1;

Fig. 3 is a side view of a part of Fig. 1 showing the mold plates removed in part to illustrate the novel mold construction;

Fig. 4 is a view of part of Fig. 1 with certain elements omitted for clarity;

Fig. 5 is an enlarged detail of a part of Fig. 1 showing the novel arrangement of electrical contacts;

Fig. 6 is an enlarged detail of a part of Fig. 1 showing the novel means employed for starting formation of the ingot and for counterweighing the same;

Fig. 7 is an enlarged sectional view of the pouring spout shown in Fig. 1; and

Fig. 8 is a circuit diagram of a novel relay circuit for use with the embodiment of Fig. 1.

In the accompanying drawings, in which like reference numerals designate like parts, the machine is mounted over a pit 10 into which the ingot moves from the molds. Pit 10 may be of any suitable size and depth depending upon the length of the ingot to cast. It is of course apparent that instead of using a pit the entire machine can be elevated to allow an ingot of suitable length to move from the molds. As shown, however, beams 11 are secured to the top of pit 10 and support machine base elements 12. Secured to base elements 12 are vertical frame members 13 and 14 extending parallel to each other. Bearings 15 and 16 are secured to frame member 13 and member 14 has aligned bearings 17 and 18 secured thereto. A shaft 19 is mounted for rotation in bearings 15 and 17 and is driven by worm gear 20 suitably mounted thereon. A shaft 21 is mounted for rotation in bearings 16 and 18 and has suitably secured to it a brake drum 22 engaged by brake band 23 adjustably mounted on frame 14 at 24.

Sprocket wheels 25 and 26 are mounted on and secured to shaft 19 and sprocket wheels 27 and 28 are mounted on and secured to shaft 21. A chain 29 is mounted upon sprockets 25 and 27 and a second chain 30 is mounted upon sprockets 26 and 28. A plurality of mold forming bars 31 are suitably secured to chains 29

and 30 for movement therewith and for limited movement with respect thereto.

As seen in Fig. 1, a similar mechanical arrangement is provided to support and carry a plurality of mold forming bars 32 parallel to and spaced from mold bars 31 in the mold forming area. This mechanism includes bearings 33 and 34 secured to frame 14, corresponding bearings not shown being carried by frame 13, and shafts 35 and 36 are mounted for rotation in these bearings. Shaft 35 has worm gear 37 secured thereto and shaft 36 has brake drum 38 mounted thereon and engaged by brake band 39 which is adjustably mounted at 40 on frame 14. A sprocket 41 is mounted on shaft 35 and spaced from sprocket 41 and mounted on shaft 35 is a second sprocket not shown. Shaft 36 supports a similar pair of sprockets one of which is shown at 42. A pair of chains engage the corresponding sprockets, one of which, chain 43, engages the sprockets 41 and 42, the other chain not being shown, and as before referred to a plurality of mold forming bars 32 are secured to these chains for movement therewith and for limited movement with respect thereto.

Frame 13 also carries bearings 45 which rotatably support a shaft 46. Worms 47 and 48 are mounted on shaft 46 and engage worm gears 20 and 37 respectively. A pulley 49 is also secured to shaft 46 and is driven by belts 50 and 50' and gear ratio changing device 80 as will more fully appear hereafter.

A mold side member 51 is supported between the mold bars 31 and 32 in the mold forming area, as by brackets 52 and 53 secured to frame 14, said side member 51 being of a cross sectional dimension corresponding to the spacing between mold bars 31 and 32. Said mold bars 31 and 32 are in sliding engagement with the opposite faces of said side member 51 and are held against said member 51 by auxiliary frame members 52' and 53' (Fig. 4). Member 51 is hollow as shown at 54 (Fig. 3) to receive cooling water admitted at 55 and withdrawn at 56, and is provided with an aperture 57 to receive a suitable pouring spout 58. Aperture 57 is located approximately $\frac{1}{4}$ to $\frac{1}{3}$ the length of the adjacent reaches of the mold bars 31 and 32 from the top of their coming into parallelism.

A similar side member 59 (Fig. 5) at the opposite side of the mold cavity is supported between the mold bars 31 and 32 by brackets secured to frame 13, and the mold bars 31 and 32 are held in sliding engagement with said member 59 by auxiliary frame members not shown but identical with members 52' and 53'. Side member 59 is also hollow and cooling water is admitted thereto at 60 and withdrawn at 61. Side members 51 and 59 are not parallel but diverge slightly from top to bottom for purposes to be explained hereafter. Side members 51 and 59 with mold bars 31 and 32 sliding over them therefore define a mold cavity of more or less rectangular shape and of small cross sectional dimensions as compared to its length.

As seen in Fig. 7 spout 58 is a more or less rectangularly shaped open box of any suitably heat resistant material provided with a nose 62 to fit snugly in aperture 57 and with an inwardly extending partition 63 having an under surface 64 substantially parallel to the bottom of spout 58 and an upper surface 65 arranged at an angle thereto.

Mold bars 31 and 32 are surface conditioned before moving to the mold forming area by air jets

66 which dry them, by rotating brushes 67 driven by motor 68 and belts 69 and 70 which clean them, and by sprays 71 which coat them with suitable lubricating material. Said brushes 67 are journaled for rotation in frame extensions 72. The sprays 71 receive their lubricant from reservoirs 73 through 74. Air under pressure is supplied to sprays 71 through pipes 75 and the lubricant in reservoirs 73, graphite and kerosene being preferred, is kept mixed by air jets 76. The area of bars 31 and 32 being sprayed may be provided with a shield 77 so that the lubricating spray will not be deflected. The mold bars 31 and 32 may be cooled in the mold forming area by any suitable number of water jets 78 spraying cooling water directly upon the backs of bars 31 and 32. If desirable these jets may be replaced by cooling manifolds of any suitable design in direct contact with the backs of bars 31 and 32.

20 Main machine motor 79 drives through any suitable variable gear ratio changing device 80 which in turn drives belt 50 through additional speed reducing gearing or belts as desired and generally indicated at 50'. Gear ratio changing device 80 is driven by a three phase motor 81 driving pulley 82, belt 83 and pulley 84 secured to the shaft 85 for operating the gear ratio changing mechanism. Cable 86 leading from relay housing 87 supplies motor 81 with current.

25 Current is supplied to motor 79 through cable 88, fuse box 89, switch 90 and cable 91. Motor 68 is supplied with current from fuse box 89 through cable 92, switch 93 and cable 94.

Water is supplied to the sprays 78 and mold side members 51 and 59 are supplied with water by pipe 95 leading from any suitable source of water. Pipe 96 supplies air under pressure to jets 66, sprays 71 and jets 76. Gas is supplied through pipe 98 to a burner 97 (Fig. 2) designed to cover spout 58 with flame during pouring to decrease oxidation of the molten metal and maintain the temperatures adjacent the aperture 57 at approximately pouring temperature. A suitable control panel 98' may be provided with manually operable valves 99 to regulate the supply of air, water and gas.

As shown in Fig. 6 means are provided for counterbalancing the weight of the ingot as it moves out of the mold, comprising pulleys 100 journaled 35 for rotation on frame members 13 and 14 near the base of the machine and supporting cables 101. Cables 101 carry between them a tray member 102 designed to receive the bottom edge of the casting as it leaves the mold area and to move 40 in tracks 103 extending downwardly into pit 10. Cables 101 carry weights 104 at their ends and pass freely through a plurality of weights 105. Weights 105 are shown as of progressively increasing length from bottom to top of pit 10 and 45 are supported in spaced relation upon brackets 106 carried by racks 106. Oppositely disposed racks 106 diverge from bottom to top of pit 10 corresponding to the increasing lengths of weights 105. As the ingot leaves the mold it will 50 engage tray member 102 and move it downwardly in pit 10 against the action of weights 104. As the ingot increases in length and weight, the weights 104, moving upwardly, will progressively pick up weights 105 thus counterbalancing the 55 increasing weight of the ingot. Knowing the size and weight of the finished ingot the weights 104 and 105 can be nicely calculated to obtain an exact counterbalance. After pouring is completed and the end of the ingot leaves the machine the ingot may be lifted from pit 10 by any

suitable means. As the ingot leaves pit 10 tray 102 moves upwardly under the action of weights 104 and 105 moving downwardly in pit 10 and weights 105 are returned progressively in order of their lengths from longest to shortest to their positions on brackets 106.

A dam member 107 is placed between mold bars 31 and 32 and mold members 51 and 59 just beneath aperture 57 before pouring is commenced to dam the mold area at the start of formation of the ingot as will more fully appear hereafter. Member 107 is provided with dovetail apertures 108 in which the molten metal of the ingot is cast to lock member 107 to the ingot. The length of member 107 is approximately that of the distance between members 51 and 59 but because members 51 and 59 diverge from top to bottom as above described member 107 is provided with block 109 resiliently urged by spring 110 into engagement with member 59 and its thickness is equal to the distance between the mold bars 31 and 32 in the mold cavity. Member 107 is easily removed from the cast ingot and may be used repeatedly.

Relay housing 81 contains a relay circuit shown diagrammatically in Fig. 8. This circuit includes a pair of electrodes 111 and 112 mounted in a frame 113 supported by hooked rods 114 designed to engage a cross member 115 of the machine frame to support electrodes 111 and 112 between the mold side members 51 and 59 and between the mold bars 31 and 32 in the mold forming area. Electrode 112 is of such a length that it will extend to a point slightly below the bottom of aperture 57 and electrode 111 is slightly longer than electrode 112. In a machine casting an ingot approximately seven inches wide and $\frac{1}{2}$ " thick this difference in length may approximate $\frac{1}{4}$ ". Wires 115 and 117 lead from electrodes 111 and 112 respectively to a suitable electric connector 118 and from connector 118 lead to the relay circuit. Wire 117 is connected to coil 119 of a solenoid operated switch 120 which is normally open. Coil 119 is connected by wire 121 to wire 122 leading to induction coil 123. Coil 123 is grounded at 124. Wire 116 leads to one side of coil 125 of a solenoid operated switch 126 which is normally closed. The other side of coil 125 is connected by wire 127 to wire 122.

Induction coil 128 is inductively associated with coil 123 and is connected by wire 129 to wire 130 from a source of electric energy, and is connected by wire 131 to wire 132 from a source of electric energy. Wire 133 also leads from a source of electric energy. A wire 134 connects wire 129 with one side of switch 120 and wire 135 connects the other side of switch 120 to one side of coil 136 of a three contact solenoid operated switch 141 which is normally open. The other side of coil 136 is connected by wire 137 to one side of limit switch 138, the other side of which is connected by wires 139 and 140 to wire 131. Limit switch 138 is normally closed and is opened by the change speed mechanism 83 when it is moved to its position of greatest speed. For this purpose the visual speed indicator 141' of mechanism 83 may be used to open switch 138 in any suitable way.

One side of switch 126 is connected by wire 142 to wire 134 and its other side is connected to one side of coil 143 of a three contact solenoid operated switch 144 which is normally open. The other side of coil 143 is connected to one side of limit switch 145 by wire 146. Limit switch 145 is normally closed and is opened by indicator 141'

when the change speed mechanism 80 is moved to its position of slowest speed. The other side of limit switch 145 is connected to wire 140.

Switch 144 is provided with three contacts 147, 148 and 149 and switch 141 is provided with three contacts 150, 151 and 152. One side of contact 147 is connected to the corresponding side of contact 152 by wire 153 which is connected to wire 130. Corresponding sides of contacts 148 and 151 are connected by wire 154 which is connected to wire 132 and corresponding sides of contacts 149 and 150 are connected by wire 155 which is connected to wire 133. The other sides of contacts 147 and 150 are connected by wire 156 and then to one pole of three phase motor 81 by wire 157. The other sides of contacts 148 and 151 are connected by wire 158 and then by wire 159 to another pole of motor 81. The other sides of contacts 149 and 152 are connected by wire 160 and then by wire 161 to the third pole of motor 81.

With the mechanism and circuits of the present invention set up and connected as above described when an ingot is to be poured the several motor circuits are closed, gas jet 97 lit and air admitted

25 to the several air jets. Motor 68 rotates brushes 67 to clean the mold bars 31 and 32, jets 66 dry the mold bars 31 and 32 as they pass by and jets 71 spray lubricant on the bars. Motor 79 drives through speed change mechanism 80, which in 30 its slowest speed position, and mechanism 80 drives worms 47 and 48 through belts 50' and 50. Rotation of worms 47 and 48 rotates worm gears 20 and 37 rotating shafts 19 and 35 which in turn rotate their associated sprockets and drive 35 chains 29, 30 and 43 moving the mold bars 31 and 32 downwardly over mold side members 51 and 59. Rotation of chains 29, 30 and 43 also rotates their supporting sprockets on shafts 21 and 36 rotating these shafts and rotating brake 40 drums 22 and 38 against the action of brake bands 23 and 39. The braking of shafts 21 and 36 forces the sprockets on shafts 19 and 35 to push the mold bars 31 and 32 downward through the mold forming area. As mold bars 31 and 32 are mounted for some movement relative to their supporting chains they are closely packed together in the mold area by this pushing action providing an almost continuous and uninterrupted mold surface producing an ingot having very smooth surfaces. When the mold bars 31 and 32 are in condition for pouring, i. e., pre-heated when required and properly cleaned and lubricated, dam member 107 is started down between the mold bars 31 and 32 and side members 51 and 59 and is held in position by the pressure exerted on it by mold bars 31 and 32. The machine is stopped as dam member 107 approaches aperture 57. Contacts 111 and 112 are then hung down into the mold area from member 115 as above described, the machine restarted and molten metal introduced into spout 58. During pouring spout 58 is kept almost level full of molten metal. This metal pours through nose 62 into the mold area and interlocks with dam 107 and congeals. Meanwhile dam 107 is moving 55 downward with the mold bars 31 and 32 and the ingot is being continuously cast. Water cooling jets 78 may be turned on at any suitable time to prevent overheating of mold bars 31 and 32 or this may be done mechanically and automatically as the ingot leaves the bottom of the machine by causing the ingot to trip a valve 162 common to all the jets 78 (Fig. 4). As the ingot leaves the bottom of the machine it is picked up 60 by tray member 102 and further downward move-

65

70

75

ment of the ingot is counterbalanced by weights 104 and 105 as above described to prevent the weight of the ingot from increasing its speed of movement out of the mold cavity.

As indicated above, mold side members 51 and 59 diverge slightly from top to bottom. As the ingot is poured it congeals and takes shape in the area just below aperture 57. As the ingot moves downwardly this divergence reduces the friction between the ingot and the members 51 and 59 reducing the power required to drive the machine.

As pointed out above the change speed mechanism 80 is designed to normally run at its lowest speed ratio so that as pouring starts the mold bars 31 and 32 are traveling at their slowest possible speed. This speed is calculated slightly below the normal rate of pour from spout 58 so that the speed change mechanism 80 may regulate the speed of mold bars 31 and 32 to the rate of pour. If the rate of pour from spout 58 could be kept constant, no change of the speed of movement of mold bars 31 and 32 would be required, as the speed could be pre-set to equal the rate of pour. However, it is physically impossible to keep the pouring rate constant and as a result the height of the molten metal in the mold cavity will vary. As casting progresses suppose the rate of pour increases and molten metal contacts the lower electrode 111. A circuit is then closed through the molten metal, electrode 111, wire 116, coil 125, wires 127 and 122, coil 123 and ground 124 and the current which is then induced in coil 123 passes to coil 125 and opens switch 126. If the height of the molten metal increases until electrode 112 is contacted then coil 119 is energized through the circuit comprising the molten metal, electrode 112, wire 117, coil 119, wire 121, wire 122, coil 123 and ground 124 and switch 120 is closed energizing coil 136 through the circuit wires 130, 129, 134, switch 120, wire 135, coil 136, wire 137, closed limit switch 138, wires 139, 140, 131 and 132. Energization of coil 136 closes three contact switch 141 and three phase motor 81 is energized and, driving through belt 83, continuously shifts speed changer 80 to a higher speed increasing the speed of movement of bars 31 and 32 and of the ingot. This speed increase moves indicator 141' away from limit switch 145 and allows limit switch 145 to close. The speed continues to increase until the speed of the ingot is such that the molten metal no longer contacts electrode 112, or until indicator 141' opens limit switch 138. When the molten metal no longer contacts electrode 112 coil 119 is de-energized, switch 120 opens, coil 136 is de-energized and switch 141 opens, de-energizing motor 81 and motor 81 stops. In either case the change speed indicator will remain at the speed setting at which the circuit was broken since breaking of the circuit stops motor 81 but does not reverse it. If this speed proves too fast and the level of the molten metal drops below contact 111 coil 125 is de-energized and switch 126 closes. As limit switch 145 is now closed coil 143 is energized through the circuit wires 130, 129, 134, 142, switch 126, coil 143, wire 146, switch 145 and wires 140, 131 and 132, and switch 144 is closed energizing and reversing the three phase motor 81. Speed change device 80 is now driven by belt 83 continuously to lower the speed ratio slowing down the speed of the mold bars 31 and 32 and of the ingot. Speed reduction continues until the level of the molten metal again contacts electrode 111 energizing coil 125 and opening switch

126 at which time switch 144 reopens and motor 81 stops or until limit switch 145 is opened by indicator 141'. In either case the speed of mold bars 31 and 32 continues at the speed of the moment the circuit was broken since breaking the circuits stops motor 81 but does not reverse it until electrode 112 is again contacted by the molten metal. Since the difference between electrodes 111 and 112 is on the order of $\frac{1}{4}$ " this speed change mechanism allows a most accurate maintenance of level of the molten metal in the mold resulting in ingots of very uniform characteristics.

As an example of the operation of this machine 180 pound runs of 80-20 brass have been cast at 2225° F. at an average rate of 40 inches per minute. The resulting ingots were approximately 12 $\frac{1}{2}$ feet long, 7 inches wide and $\frac{1}{2}$ inch thick and exhibited unusually uniform crystalline characteristics.

It will now be apparent that the present invention provides a novel apparatus for continuous casting of metals, which is of certain and uniform operation, by the pouring of the molten metal between vertical moving mold plates in a mold area of relatively small cross sectional dimensions as compared to its length, by regulating the speed of the molds with respect to the rate of pour of the molten metal, by counterbalancing the weight of the ingot as it issues from the mold area, by reducing the friction of the ingot in the mold, by damming the mold area at the start of pouring and by packing the mold bars together in the mold area to provide uninterrupted mold surfaces.

To those skilled in the art changes in or modifications of the above disclosed illustrative embodiment of the present invention will now be suggested without departing from the present inventive concept. Therefore to determine the scope of this invention reference should be had to the appended claims.

What is claimed is:

1. Means for controlling the level of molten metal in the molding chamber of a continuous casting device having means for admitting molten metal to the molding chamber and means for removing solidified metal from the molding chamber comprising: variable speed means driving the metal removing means, said variable speed means including a control member movable through a range of controlling positions for setting the driving speed; a reversible electric motor for controlling the position of said control member, said motor being adapted to move said control member in a speed-increasing direction upon rotation of said motor in one direction and to move said control member in a speed-decreasing direction upon rotation in the opposite direction; a pair of electrodes projecting into the molding chamber, the lower extremity of one of said electrodes being below the lower extremity of the other of said electrodes; an electric circuit including said other electrode and the molten metal in the molding chamber for energizing said motor for rotation in said one direction when said other electrode is contacted by the molten metal; a second electric circuit for energizing said motor for rotation in said opposite direction; and electric means including a circuit through said one electrode and the molten metal for opening said second circuit when said one electrode is contacted by said molten metal.
2. Apparatus as claimed in claim 1 wherein the first said circuit includes switch means coop-

erable with said control member for precluding energization of said motor for rotation in said one direction while said control member is in its maximum speed position; said second circuit including switch means cooperable with said control member for precluding energization of said motor for rotation in said opposite direction while said control member is in its minimum speed position.

3. Means for controlling the level of molten metal in the molding chamber of a continuous casting device having means for admitting molten metal to the molding chamber and means for removing solidified metal from the molding chamber comprising: variable speed means driving the metal removing means, said variable speed means including a control member movable through a range of controlling positions for setting the driving speed; a reversible electric motor for controlling the position of said control member, said motor being adapted to move said control member in a speed-increasing direction upon rotation of said motor in one direction and to move said control member in a speed-decreasing direction upon rotation in the opposite direction; a normally open electric circuit for energizing said motor for rotation in said one direction; means for closing said normally open circuit when the molten metal in the molding chamber rises to a preselected level, said means including a normally open switch, electrically operable means adapted when energized to close said normally open switch, an electrode in the molding chamber, and circuit means including said electrode and the molten metal in the molding chamber for energizing said electrically operable means when said electrode contacts the molten metal; a normally closed electric circuit for energizing said motor in said opposite direction; and means for opening said normally closed circuit when the molten metal in the molding chamber rises to a second preselected level, said last named means including a normally closed

switch, electrically operable means adapted when energized to open said normally closed switch, a second electrode in the molding chamber having its lower extremity disposed below the lower extremity of the first said electrode, and circuit means including said second electrode and the molten metal in the molding chamber for energizing said last named electrically operable means when said second electrode contacts the molten metal.

5. Apparatus as claimed in claim 3 wherein the first said circuit means includes switch means cooperable with said control member for precluding energization of the first said electrically operable actuating means while said control member is in its maximum speed position; the second said circuit means including switch means cooperable with said control member for precluding energization of the second said electrically operable actuating means while said control member is in its minimum speed position.
